TRANSPLANTING TOOL

Victor E. Bredenberg, Springfield, Mass.

Application August 4, 1958, Serial No. 52,024

Term of patent 14 years

(Cl. D35—2)

Fig.1.

Fig.2.

Fig.3.

Fig. 1 is a side elevational view of a transplanting tool embodying my new design;

Fig. 2 is a front elevational view thereof; and

Fig. 3 is a bottom plan view of the tool.

The characteristic features of my design for the tool disclosed reside in the gripping members in association with the handle portions, as shown.

I claim:

The ornamental design for a transplanting tool, substantially as shown and described.
